UNITED STATES PATENT OFFICE

WALTER A. FRANTZ, OF CLEVELAND HEIGHTS, OHIO, ASSIGNOR TO THE APEX ELECTRICAL MANUFACTURING COMPANY, OF CLEVELAND, OHIO, A CORPORATION OF OHIO

GEARING

Application filed July 11, 1929. Serial No. 377,366.

The invention relates to gearing and especially to gear mechanism for clothes washing machines and has for its object the provision of a new, improved and simplified device for adjusting a rack toward and from its pinion, said device being operable from a position at one end of the pinion; the provision of a gear mechanism wherein the machining operations are particularly few and simple; the provision of a gear mechanism having particular advantages in quantity production; the provision of means for taking up looseness in a rack-and-pinion drive from the outside of the gear-box without permitting oil leakage; while further objects and advantages of the invention will become apparent as the description proceeds.

In the accompanying drawing Fig. 1 is a vertical sectional view through part of the bottom of a washing machine containing my improvements; Fig. 2 is a horizontal sectional view corresponding to the line 2—2 of Fig. 1; and Fig. 3 is a separated perspective view of some of the parts.

1 denotes the sheet-metal bottom of the tub which is here formed at its center with an upwardly embossed portion 2 centrally apertured at 3. Located beneath the tub bottom is a horizontal gear-box 4 having the top-plate 5 bolted thereto and apertured at 6 for the reception of the flange 7 carrying the packing-box 8 whose upper end carries the threaded shoulder 9 projecting through the opening 3 and the flange 10 underlying the tub bottom adjacent to the opening. The parts are held tight and leak-proof by the nut 11.

Threaded into the mouth of the packing-box 8 is the gland nut 12 and journaled in this nut and packing-box is the rock-shaft 13 to which is keyed the pinion 14 meshing with the rack 15. Formed in the bottom wall of the gear-box 4 coaxially with the packing box 8 is an aperture 16 in which is rotatably seated the hollow neck 17 of an adjusting member constituting a kind of cage. Interiorly this neck is formed for the reception of the end portion 18 of the shaft 13, and the end of the neck is preferably closed as shown at 19 so as to prevent

any possible leakage of oil around the shaft. Exteriorly the extreme end of the neck is provided with a prismatic head 20 to enable rotation thereof, and near that head with screw-threads 21 for the reception of a jam-nut by which the neck is held in adjusted position, leakage being prevented by a gasket 22. Inside the gear-box the neck terminates in a shoulder 23 constituting the end of a hollow body composed of two vertically-spaced circular ribs 24 defining between them the open space 25 and rigidly together at one side by the longitudinal web 26. The internal diameter of this body is sufficient freely to receive the pinion 14 as shown in Fig. 2, and the exterior of said body is cylindrical but slightly eccentric to that pinion as also shown in Fig. 2. Oscillatably mounted on the exterior of this body 24 is the hub 30 of a stirrup whose two side-pieces 31—31 are carried by a wear-plate 32 embracing the rear face of the rack 15 and holding the same against the pinion.

To adjust the rack against the pinion it is necessary merely to release the jam-nut 21 and rotate the head 20 slightly with a wrench afterwards tightening up the nut. Inasmuch as the eccentricity is not made at all great it is possible for the rack, and stirrup to oscillate about the pinion to some extent without binding. It will be understood that any convenient mechanical movement can be employed for reciprocating the rack.

Among the important practical advantages of this invention is the fact that all the essential machining of the gear-box can be effected with a single chucking of the article and from one side since it is only necessary that the aperture 16 be coaxial with the aperture 6 and perpendicular to the seat which is preferred for the plate 7. The cage and neck can also be made sufficiently accurate by simple means, and the packing-box element is also easy to make, and align therewith. The tolerances permitted by this design are such as to facilitate quantity production and the shaft and packing box element can be assembled in quantity and applied to any gear-box indiscriminately. Besides the device is not subject to oil leakage.

I have shown the upper end of the shaft 13 as provided with a driving head 33 to which is applied a washing element 34. It will be understood that changes in details 5 can be made within the scope of my invention and I do not limit myself to the exact construction shown except as I have recited the same in detail in my several claims.

Having thus described my invention what 10 I claim is:

1. In a mechanical movement, the combination with a rack-and-pinion of a hollow cage surrounding said pinion, and a stirrup movably mounted on said cage and having a 15 part engaging said rack to hold the same against said pinion, said cage having portions of its wall formed to enable uninterrupted engagement between said rack and said pinion and having its exterior eccentric 20 relatively to said pinion to enable adjustment of the distance between said rack and said pinion, said cage also having a prismatic portion projecting beyond said pinion at one end whereby it may be turned to effect 25 such adjustment.

2. In a mechanical movement, the combination with a rack-and-pinion of a hollow cage surrounding said pinion, a stirrup movably mounted on said cage and having a part 30 engaging said rack to hold the same against said pinion, said cage having portions of its wall formed to enable uninterrupted engagement between said rack and said pinion and having its exterior eccentric relatively to 35 said pinion to enable adjustment of the distance between said rack and said pinion, a housing surrounding both said rack and pinion, and means operative from the exterior of said housing to adjust said cage angularly 40 about said pinion.

3. In a mechanical movement, the combination with a rack-and-pinion of a hollow cage surrounding said pinion, said cage having a neck coaxial with said pinion, a housing 45 for said rack and pinion, said housing having in its wall an aperture for said neck and said neck being formed outside of said housing with provisions for the reception of a tool for adjusting the same angularly 50 about its axis, and means located inside said housing and operatively engaging said cage and said rack for varying the distance between said rack and said pinion as said cage is rotated about its axis.

4. In a mechanical movement, a gear-box 55 having a bearing in one wall and an aperture in the opposite wall in line with said bearing, a rock-shaft journaled in said bearing and traversing said gear-box, a pinion carried by said shaft inside said gear-box, a hollow neck rotatably mounted in said aperture, said shaft projecting into said neck, a rack inside said gear-box meshing with said pinion, an element inside said gear-box engaging 60 said rack and holding it against said

pinion, said neck being formed outside of said gear-box with provisions for the reception of a tool for adjusting the same about its axis and inside of said gear-box with provisions for engaging said element and thereby drawing 70 said rack against said pinion.

5. In a mechanical movement, a gear-box having a bearing in one wall and an aperture in the opposite wall in line with said bearing, a rock-shaft journaled in said bearing and traversing said gear-box, a pinion carried by said shaft inside said gear-box, a neck rotatably mounted in said aperture and having a prismatic head, means for holding 75 said neck in adjusted position, a rack inside said gear-box and engaging said pinion, and means inside said gear-box engaging said rack and operatively secured to said neck for moving said rack toward said pinion as said neck is turned.

6. In a washing machine, a gear box having in one side wall a shaft bearing and in the opposite side wall an aperture, a shaft journaled in said bearing, a toothed pinion carried by said shaft inside said gear-box, a second toothed member inside said gear-box meshing with said pinion, and an adjusting member having a neck located in said aperture, a body inside said gear-box and an adjusting head outside said gear-box, said body having a part operatively connected to said second toothed member and adapted when said neck is turned to move said second toothed member toward or from said pinion.

In testimony whereof I hereunto affix my 100 signature.

WALTER A. FRANTZ.
